(57) **CLAIM**

The ornamental design for a water bottle with sleeve, as shown and described.

DESCRIPTION

FIG. 1 is a front view of a water bottle with sleeve, showing my new design.

FIG. 2 is a top view thereof.

FIG. 3 is a bottom view thereof; and,

FIG. 4 is a bottom perspective view thereof.

The broken lines in the figures illustrate the portions of the water bottle with sleeve that form no part of the claimed design.
